UNITED STATES PATENT OFFICE

2,434,062

REFRIGERANT TANK FOR REFRIGERATOR CARS

Edwin R. Battley and George E. McCoy,
Montreal, Quebec, Canada

Application March 17, 1945, Serial No. 583,354

7 Claims. (Cl. 62—17)

1

This invention relates to railway refrigerator cars used to transport commodities requiring refrigeration in transit, and especially to such cars used for commodities necessitating a temperature of thirty degrees or less, en route, such as frozen foods.

The invention is an improvement over Patent No. 2,136,999, of November 15, 1938, wherein a refrigerant container is located adjacent the roof and a side wall of the car and a partition is located below the refrigerant container to provide an air cooling space therebetween and wherein the air in said space, being cooled by the refrigerant in said container, descends through flues associated with said side wall, into a space provided below the lading, and, being warmed by the lading, rises through the lading space to the cooling space where the cycle is repeated. In such cars wet ice is used as the refrigerant when transporting commodities requiring not less than forty-five to fifty degrees temperature, and salt is used with the ice to obtain brine when lower temperatures are required, a 30% ratio of salt to ice producing brine at about minus six degrees temperature which gives the brine great heat absorbing capacity.

When brine is used as the refrigerant, a solid or imperforate refrigerant container or tank is used to retain the brine in the tank and thereby obtain the full benefit of its heat absorbing capacity. Overflow holes are provided in such tanks to limit the amount of brine therein and a drain plug for cleaning the tanks of debris and for inspection is provided.

It has long been known that a brine solution accentuates corrosion of metal, particularly steel, in contact therewith, and experience has shown that a concentrated solution causes considerable corrosion of the metallic flues in the walls of a top bunker car, even though said flues are galvanized. When such flues corrode, the jolting of the car opens up the corroded parts, allowing moisture to pass therethrough and be absorbed by the insulation, thereby reducing its effectiveness as insulation, and adding weight which must be carried about with the car, and which adds to the overhead cost of operating the car.

It is the principal object of the invention to utilize the advantages of the air and liquid circulating system, as set forth in Patent No. 2,136,999, supra, and at the same time confine the corrosion to a relatively small number of places, thereby materially reducing the cost of maintenance of the car.

It is another object of the invention to provide

2
overflow and drain openings for a refrigerant container of such a car and to surround said openings with means whereby liquid which overflows or is drained from said container is conducted into a certain flue only. A further object of the invention is to arrange said means so that air circulating over and about said container may also move through (and around) said means into the same flue to which the overflow and drained liquid is conducted by said means. Thus said conduit means does not interfere with the free movement of cooled air into the wet flue.

By this arrangement the other vertical flues associated with the walls of the refrigerator car are kept dry, and, therefore, free from corrosion. In other words, the corrosion is confined to or concentrated in a very few of the several flues in the car.

Other objects and advantages of the invention will appear in the following description thereof.

Referring now to the accompanying drawing, forming part of this application, and wherein like reference characters indicate like parts:

Figure 1 is a transverse section through part of the roof and side wall of a railway refrigerator car incorporating the invention.

Figure 2 is a horizontal section on line 2—2 of Figure 1 through the side wall of a refrigerator car to which the invention is applicable.

Figure 3 is a transverse section through part of the wall and floor of a refrigerator car to which the invention is applicable.

Figure 4 is an enlarged section through the roof, side wall and refrigerant container of a top

35 bunker refrigerator car showing the improved means for conducting overflow liquid and drain liquid from the refrigerant container to one of the side wall vertical air flues.

Figure 5 is a modified form of duct forming part of the invention wherein the duct is made of one piece of metal comprising a single unit.

The invention is adaptable to a refrigerator car having spaced apart insulated walls, one of which is shown at 1; an insulated roof 2; an insulated floor 3; a foraminous floor 4 above the floor 3 providing an air distributing space 6 between said foraminous floor and insulated floor.

A liquid refrigerant container 1 is positioned adjacent the roof 2 and side wall 1 to form an air circulating space 8—9 therebetween. Since the invention is designed for use with water ice or brine as the refrigerating medium, these containers are of the solid type, provided only with the filling opening 10; overflow opening 11; and drain opening 13, provided with a removable stop-

per or plug 14. The hatch opening through the roof is shown at 15 and, of course, the filling opening 16 in the container is positioned immediately therebelow as customary. A plurality of such containers is provided on each side of the car and, of course, there is a hatch opening for each container through which said containers may be serviced.

The side walls of the car are constructed substantially as shown in Figure 2 wherein 16 is the outer sheathing; 17 are the vertically disposed outer side posts to which said sheathing is secured; 18 is the insulating material and 19 are the spaced inner posts which are generally staggered in relation to the outer posts 17, preferably occurring in a plane midway therebetween and which overlap wooden inner nailing posts 20, to which the inner sheathing 21, preferably plywood, is removably secured.

A metallic sheet 25 paneled substantially as shown in Figure 2 to provide vertical flues 26 is interposed between the posts 19-20 and the inner sheathing 21, and is removably secured to said nailing posts 20. These sheets 25 are, of course, galvanized for the purpose of resisting the corrosive action of brine or other liquid solution draining therethrough from the containers 7. Sometimes they are covered with a coating highly resistant to the corrosive action of the liquid from the particular refrigerant used. Notwithstanding such protective measures these flue sheets 25 corrode much faster than the other metal parts of the car which do not have such protection.

Therefore, the sheet 25 is preferably made in sections, since it is an object of the invention to confine the overflow and/or drain from each tank to a certain flue only, and to accomplish this object there is shown a pair of spaced vertical kerfs 29 within the inner faces of an adjacent pair of posts 20. The vertical edges of the each flue sheet 25 are provided with outwardly extending flanges 30 which fit within said kerfs 29, and, when the inner sheathing is in place, of course, said flanges cannot be removed from the kerfs. Consequently when any flue sheet needs replacing it may be removed independently of the others by simply first removing the inner sheathing.

The overflow openings 11 and drain opening 13 of each container 7 are located directly over an adjacent wet flue 26, and there is shown in Figure 4, a spout-like duct 35 secured to a side wall 36 of the tank about said overflow openings 11. The liquid overflowing through said overflow holes is thus trapped in said ducts and must pass downwardly therethrough. This duct 35 may be secured directly to the side wall 36 of the tank or to the tank supporting angle 37. The duct 35 is substantially rectangular in cross section and wide enough to enclose the preferably three overflow openings 11. The bottom of the duct is constricted to about one-half width, as at 38, forming a relatively wide spout-like open terminus.

The drain opening 13 of the tank is preferably formed at the juncture of the side wall 36 of the tank with the bottom of the tank or container and is preferably located directly under the overflow holes 11. There is also provided an enclosure or duct 39 formed about the drain opening 13 having an upper open end 40 into which the lower end 38 of the duct 35 extends and, therefore, discharges thereinto. The open end 40 is much larger in cross sectional area than the end 38 of enclosure 35 so that air, circulating in the passageway 8-9, may also enter said open end 40

about the enclosure 35 and pass downwardly therethrough. The lower open end 42 of enclosure 39 is offset outwardly so as to extend into the upper end of wet flue 26 and thus all liquid from either the overflow holes 11 or drain 13 of each container is confined within one flue 26, which is designated as the "wet flue." No liquid, therefore, descends through any other flue, which other flues (27) are consequently considered as "dry" flues. Since the overflow brine has a temperature of zero, or below, it absorbs considerable heat from the air as it descends through the wet flues 26 and as it lays on the floor of the car before it escapes from the car through outlets provided for that purpose.

It is obvious that the duct may be made in one unit and function similarly to that just described and thus Figure 5 shows a vertical section through a single duct 45 about both the overflow 11 and drain openings 13, which duct extends within the upper end of the wet flue 26 and thus conducts all liquid from the overflow and/or drain openings thereinto.

The ducts 35 and 39 are preferably solely attached to and solely supported by the tanks 7 (as shown in the drawings) so that they may be installed in the car with the tank and also be removed from the car with the tank. Furthermore, in such an arrangement any relative movement between the tank and/or the side wall of the car, due to service movements of the car, does not have a tendency to crack or distort the means attaching these ducts 35 and/or 39 to the tank. A further object of this arrangement is so that the tank and the ducts 35 and 39 may be simultaneously dipped in liquid spelter to galvanize them, thus assuring that no corrosion will occur at the joints between the tank and conduits.

The enclosures or ducts 35 and 39 are preferably substantially the same length (i. e., lengthwise of the car) but both are of less length than the width (i. e., lengthwise of the car) of the flue 26 into which they discharge the liquid or brine. These comparative sizes (relatively speaking) are shown in Figure 2. Such an arrangement allows air, being cooled by contact with the refrigerant container, to flow around the conduits 35 and 39 as well as through them, and conversely, the conduits 35 and 39 do not interfere with the free movement of such air from adjacent the container to the vertical flue.

The partition 44 is positioned below the refrigerant container 7 and spaced slightly therebelow, which extends from the side wall of the car to adjacent the longitudinal center of the car where it is provided with an upstanding flange 46, thereby practically enclosing the container and providing an air cooling space thereabouts. The partition inclines downwardly toward the side wall, and the upper end of the flues communicate with said air cooling space, whereas the lower ends of said flues communicate with the air distributing space 6 under the foraminous floor 4. Thus the air in the cooling space, as it is cooled by the refrigerant in said container, moves downwardly to and through said flues to said distributing space, upwardly through the foraminous floor and lading compartment back to the cooling space where the cycle is repeated.

The accompanying drawings illustrate the preferred form of the invention, though it is to be understood that the invention is not limited to the exact details of construction shown and described, as it is obvious that various modifica-

tions thereof, within the scope of the claims, will occur to persons skilled in the art.

We claim:

1. In a railway refrigerator car having a roof, a wall, a flue forming part of said wall, a liquid refrigerant container adjacent said roof and provided with overflow and drain openings; a duct communicating with said overflow and drain openings and said flue to conduct liquid from said overflow and drain openings directly into said flue.

2. In a railway refrigerator car having a roof, a wall, a flue forming part of said wall, a liquid refrigerant container adjacent said roof and provided with overflow and drain openings; and means to direct air cooled by a refrigerant in said container into said flue; a duct communicating with said overflow and drain openings and said flue to conduct liquid from said overflow and drain openings directly into said flue.

3. In a railway refrigerator car having a roof, a wall, a flue forming part of said wall, a liquid refrigerant container adjacent said roof and provided with overflow and drain openings; and means to direct air cooled by a refrigerant in said container into said flue; a duct communicating with said overflow and drain openings and said flue to conduct liquid from said overflow and drain openings directly into said flue, said duct provided with means whereby some of said air may pass through said duct into said flue.

4. In a railway refrigerator car having a wall, a roof, a plurality of vertical flues forming part of said wall, a refrigerating chamber adjacent said roof and a liquid refrigerant tank within said chamber, said wall, roof, chamber and tank being associated so that air in said chamber being cooled by a refrigerant in said tank is directed into said flues; a duct communicating with drain holes and overflow holes in said tank which directs

liquid from said holes directly into one of said flues only without preventing the flow of cooled air from said chamber into said last mentioned flue.

5. A liquid refrigerant tank for a railway refrigerator car having imperforate bottom and side walls except for overflow holes and drain holes, said tank being provided with a duct communicating with said holes and adapted to discharge liquid from said holes remote from said tank.

6. A liquid refrigerant tank for a railway refrigerator car having imperforate bottom and side walls except for overflow holes and drain holes, said tank being provided with a duct communicating with said holes and adapted to discharge liquid from said holes into vertical flues forming part of the wall of a refrigerator car.

7. In a railway refrigerator car having a wall, a roof, a plurality of vertical flues forming part of said wall, a refrigerating chamber adjacent said roof and a liquid refrigerant tank within said chamber, said wall, roof, chamber and tank being associated so that air in said chamber being cooled by a refrigerant in said tank is directed into said flues; a duct communicating with holes in said tank which directs liquid from said holes directly into one of said flues only without preventing the flow of cooled air from said chamber into said last mentioned flue.
